ELECTRIC SWITCH.

Application filed October 17, 1928. Serial No. 669,086.

My invention relates to electric switches, and particularly to a switch of the "push-through" type. Among the objects of my invention may be mentioned—

- 5 (1) The construction of a switch of the push-through type adapted for use in an electric lamp socket;
 (2) A switch mechanism of simple and economical construction;
 10 (3) A self-contained switch mechanism and supporting frame adapted to be held in position solely by a clamping engagement between the insulating members of the supporting structure;
 15 (4) Various details of construction and relation of parts hereinafter described or shown in the accompanying drawings in which—

20 Fig. 1 is a broken side elevation of an electric lamp socket in which my invention is embodied in one form;

25 Fig. 2 is a vertical section through the insulating body, the switch being shown in open circuit position;

30 Fig. 3 is a similar section showing the switch in closed circuit position;

Fig. 4 is an exploded view of the switch and body structure; and

35 Fig. 5 is a similar view of a modified construction.

The present invention may be applied to switches of various types, and its embodiment in an electric lamp socket in the accompanying drawings is merely to illustrate an appropriate utility.

As shown in Figs. 1 to 4, the socket comprises an insulating button 10 of porcelain or the like, provided with a transverse central channel 11 in one face to accommodate the switch mechanism. A second insulating member in the form of a fiber disc 12, overlies the channelled face of the button 10. Upon it rests the usual screw shell 13, over the usual bottom flange 14 of which extends the yoke 15, integral with the offset terminal strap 16 which projects through a lateral aperture in the shell and lies in the recess 17 formed in one side of the button 10. A pair of screw bolts 18 passing through holes 19 in the button 10, disc 12 and flange 14, and taking into the yoke 15, serve to maintain the shell in position and to hold all of the socket parts together.

35 The center contact 20 of the socket is mounted directly on the fiber disc 12 and is

insulated by the latter from the screw shell 13. The contact 20 is held in position by integral flanges 21 and 22, the former passing through a hole 23 in the disc, and the latter passing through a slot 24 in the disc, the ends of the two flanges being offset toward each other beneath the disc, thus riveting the contact in place. Flanges 25 extending downward from opposite sides of the contact head, overlie the body of the disc 12, and serve as spacing struts which prevent the deformation of the center contact when a lamp base is screwed down hard into the shell 13.

The circuit through the socket is made or 70 broken by the oscillating rocker 26, which in the closed circuit position (Fig. 2) enters the slot 24 in the disc 12 and engages the flange 22 of the center contact. The rocker 26 is pivoted upon the frame 27, from one 75 margin of which projects an integral lug 28 carrying a binding screw 29 that lies in the side groove 30 in the button 10. The rocker 26 is thus constantly in electrical connection with the wire terminal 29. Slidably engaged beneath the frame is a reciprocating bar 31 having at its opposite ends push buttons 32 and 33 to facilitate its manipulation. The push bar is provided with an offset push lug 34 which projects upwardly through a slot 35 in the frame, and bears against the edge of the rocker 26 opposite that which engages the center contact flange 22. The push bar also carries a plate spring 36 which, at its free end, bears against the downwardly projecting cam nose 37 of the rocker 26.

The particular shape and arrangement of these parts may be variously modified, while still embodying the underlying characteristics of my invention, but the construction 85 which I have illustrated is simple, efficient and economical. Thus, the switch frame 27 is struck from sheet metal and angled to shape. The longitudinal slot 35 for the accommodation of the body of the rocker 26 and 90 push bar cam lug 34, extends an appropriate distance from the bearing bridge 38, on which the rocker is pivoted, toward push button 32. The aperture 39 on the opposite side of the bridge 38, accommodates the lower end of 95 the rocker, and the hook which forms the open bearing 40 intermediate the contact and cam ends of the rocker which extend respectively above and below the frame. Lugs 41 and 42 upwardly offset from the body of the 100

- frame are received in channels 43 and 44 in the button 10, and with the lug 28, are engaged by the fiber disc 12, the frame and associated parts being thus held in position 5 when the disc is drawn down on the button 10 by the screws 18. The downwardly extending T-head lug 45 at one end of the frame, passes through the slot 46 in the push bar and supports the latter. The shoulders of the 10 push lug 34 of the bar 31 rest and slide upon the upper face of the frame at its opposite end. The transverse bays 47 in the slot 35 permit the lug 34 to be passed upward through the frame to assembled position. 15 The interposition of the rocker 26 between the bridge 38 and the push lug 34 limits the approach of the lug 34 toward the slot 47, and is of such dimensions as to prevent the escape of the lug through the slot 47 while 20 the rocker is in position.

The operation of the switch will be readily understood. In the "off" position of the switch (Fig. 2), the rocker 26 is held away from the contact lug 22 and against the push lug 34 by the pressure of the terminal incline α of the spring 36 which bears against the incline ω to one side of the nose of the rocker cam 37. As the push bar is shifted to the left by pressure on the button 32, the rocker 26 is lifted toward the contact 22 by its sliding engagement with the push lug 34. Simultaneously, the downward swing of the cam 37 of the rocker places the spring 36 under greater stress, and shifts the cam nose 25 across the crest 48 of the spring 36, the spring and rocker cam moving in opposite directions as the bar 31 is shifted. When the cam nose passes the spring crest 48, the opposite incline b of the spring tends to ride up the opposite incline γ of the rocker cam 37. The dimensions and relation of the parts is such that the rocker 26 is now biased with a spring snap action against the contact 22 (Fig. 3) 30 and is held in this position not only directly by the spring 36, but also by the thrust of the push lug 34. It will be noted that the movement of the push bar in this direction is stopped by the engagement of the push lug with the rocker, pivoted on the fixed frame, 35 and further, that in this position the spring 36 exerts an effort on the push bar, still urging it to the left. The rocker is therefore held firmly against the frame and makes good contact therewith and with the switch 40 contact 22.

When the push bar is shifted in the opposite direction, the push lug 34 leaves the rocker 26, which is now held against the center contact lug 22 with increasing effort by the spring 31, as the incline b thereof rides down the incline γ of the cam 37, and the spring is placed under greater stress. As the crest 48 of the spring passes the nose of the cam 37, the incline α of the spring engages the incline ω of the cam nose and biases 45

the rocker in the opposite direction. Inasmuch as the push lug 34 of the bar 31 has moved out of engagement with the rocker 26, and the latter is therefore unopposed, the turning moment exerted by the spring 36 70 upon the cam nose 37 throws the rocker away from the contact lug 22 with a snap action. Its throw to open circuit is halted by impingement against the push lug 34. A rapid and wide break between rocker and switch contact 22 is thus attained, while the spring 36 holds the rocker in open circuit position. 75

In the modification shown in Fig. 5, the operating parts of the switch mechanism are the same as those just described. The shape of the frame and the construction of the insulating body elements is altered. Thus the body comprises a pair of buttons 49 and 50 recessed on their meeting faces to afford channels 51 in which the lugs 52, 53 and 54 are accommodated, and by which the flat frame is clamped in position on the assembly of the parts. The button 49, as well as the button 50, is transversely channeled at 55 to accommodate the switch mechanism. It is also slotted at 56 to permit the rocker 57 to play therein and to engage the contact lug 58 which rests against one end of the slot 56. The other end of the contact is integral with or electrically connected to the center contact 59. In the present construction the center contact is mounted on button 49 by a through rivet 60. 90

Various other modifications will readily occur to those skilled in the art which do not depart from what I claim as my invention. 100

I claim—

1. In an electric switch, a switch contact, a pivoted rocker, a push bar slidable with respect thereto and adapted to push the rocker toward the switch contact, and a spring carried by the push bar and having a camming engagement with the rocker to complete the circuit closing travel of the latter. 105

2. In an electric switch, a switch contact, a pivoted rocker, a push bar slidable with respect thereto, and a spring carried by the latter and having a camming engagement with the rocker to throw the same away from the contact with a snap action on movement of the push bar in the same direction. 110

3. In an electric switch, a pivoted rocker, a push bar slidable with respect thereto and having a positive engagement with the rocker to swing the latter on its axis on movement of the bar in one direction, together with a spring moved by the push bar and operatively engaging the rocker to swing the latter in the opposite direction on the return movement of the push bar. 115

4. In an electric switch, a pivoted rocker having a contact portion extending to one side of its axis, and a cam portion extending to the opposite side of its axis, a push bar rectilinearly displaceable with respect to the 120 125 130

5 rocker, and mechanically engaging the latter to swing it in the direction of movement of the push bar and a spring moving with the push bar and engaging the cam end of the rocker to maintain the latter in its extreme positions at opposite ends of its throw.

10 5. In an electric switch, a pivoted rocker having a contact portion extending to one side of its axis, and a cam portion extending to the opposite side of its axis, a push bar rectilinearly displaceable with respect to the rocker, and mechanically engaging the latter to swing it in the direction of movement of the push bar, a spring carried by the push 15 bar and moving therewith, said spring having an operative engagement with the cam end of the rocker and serving to shift the rocker with snap action to its extreme positions at opposite ends of its throw.

20 6. In an electric switch, a pivoted rocker, a push bar rectilinearly movable with respect thereto, a spring carried by the push bar and engaging the rocker, said push bar engaging the rocker to positively swing the latter on its 25 axis on the displacement of the push bar in one direction, said spring having an actuating engagement with the rocker to swing the latter in the opposite direction on the return movement of the push bar.

25 7. In an electric switch, a pivoted rocker, a push bar rectilinearly displaceable with respect thereto, a lug on the push bar engaging the rocker to swing the latter on its axis on displacement of the push bar in one direction, 30 a spring moving with the push bar and operatively engaging the rocker to complete the movement initiated by the push bar lug, said spring serving on the return movement of the push bar to swing the rocker in opposite direction with a snap action after said lug has left the rocker.

35 8. In an electric switch, a slotted frame having a transverse bridge, a rocker pivoted on said bridge and working in the slot on the frame, a push bar slidably associated with the frame and having means for positively displacing the rocker on the movement of the push bar in one direction, together with a spring carried by the push bar and having a 40 camming engagement with the rocker to swing the latter in opposite direction on the return movement of the push bar.

45 9. In an electric switch, an apertured frame, a rocker pivoted thereon and having a contact portion extending above the frame and a cam portion extending below the frame, a slotted push bar rectilinearly guided on said

frame beneath the latter, an element on said push bar projecting through the slot in the frame and engaging the contact portion of the 50 rocker to swing the latter on its axis on the movement of the push bar in one direction, together with a spring carried by said push bar and engaging the cam end of the rocker to displace the rocker with a snap action in 55 opposite direction on the return movement of the push bar.

10. In an electric switch, a sheet metal frame slotted to form an integral bridge transverse to said slot, a rocker having an 60 open bearing pivoted on said bridge, and a rectilinearly movable spring engaging said rocker to constantly maintain the latter in pivotal engagement with the frame.

11. In an electric switch, a frame, a rocker 65 pivoted thereon and having a contact portion extending in one direction from its axis, and a cam portion extending in the opposite direction from its axis, together with a rectilinearly 70 movable spring engaging the cam portion of the rocker and imparting snap action thereto in opposite directions on the longitudinal displacement of the spring.

12. In an electric switch, a rectilinearly 75 movable sheet metal push bar having a lug projecting from one face thereof, together with a flat metal spring secured to the lower face of the bar and extending in the direction of its length, said lug and spring being adapted for operative engagement with an 80 associated rocker.

13. In an electric switch, a rectilinearly 85 movable push bar longitudinally slotted and having a lug projecting above the bar at one end of the slot, together with a flat metal 90 spring secured to and movable with the push bar and extending in the direction of the length of the latter beneath the slot therein for cooperation with an associated rocker playing in the slot.

14. In an electric lamp socket, an insulating disc, a screw shell resting on the disc, and a center contact carried by the disc, said center contact having flanges passing through 100 apertures in the disc and offset beneath the latter to rivet the contact member thereto, the aperture adjacent one of said flanges being shaped as a slot permitting the play of a rocker into and out of engagement with 105 said flange to make and break connection with said center contact.

In testimony whereof I have signed my name to this specification.

ARVID H. NERO.
